SLICING MACHINE

Adolph Rubin, St. Louis, Mo., assignor to Hussmann-Ligonier Company, St. Louis, Mo., a corporation of Delaware

Application April 7, 1930. Serial No. 442,097

3 Claims. (Cl. 146—158)

This invention relates generally to slicing machines, and particularly to an improved slicing machine which is provided with a reciprocating cutting element, the predominant object of the invention being to provide a slicing machine of this type which is at once of extremely simple design and highly efficient in operation.

Fig. 1 is a plan view of the improved slicing machine.

10 Fig. 2 is a front elevation of the slicing machine illustrated in Fig. 1.

Fig. 3 is a cross-section of the machine shown in Figs. 1 and 2.

15 Fig. 4 is a fragmentary sectional detail illustrating the mechanism for imparting reciprocatory movement to the cutting element of the machine.

In the drawings, wherein is shown for the purpose of illustration, merely, one embodiment of 20 the invention, A designates the improved slicing machine generally, said machine comprising a suitable base 1 which preferably is of inverted hollow construction, as shown in Fig. 3. At the forward side of the base 1 same is provided with 25 inturned extensions 2 to which suitable feet 3 are fixed, and at the rear side of said base a pair of outwardly extended brackets 4 are fixed (Figs. 1 and 3) which support a pan P. Each of the brackets 4 is provided with an upwardly ex- 30 tended portion 5 which contacts with a portion of the rear face of the base 1, said upwardly extended bracket portion being provided with centering pins 6 which are inserted into apertures in the rear wall of the base for the pur- 35 pose of locating the bracket portions with respect to the base. 7 designates screw-threaded fastening devices, one of which is associated with the upwardly extended portion of each bracket, the screw-threaded shank portion 7' thereof be- 40 ing extended through an opening in the upward- 45 ly extended bracket portion and being screwed into a screw-threaded aperture in the rear wall of the base. Each bracket 4 is provided with a circular portion 8 which provides a foot 9 which aids in supporting the machine.

At the approximate longitudinal center of the rear wall of the base 1 a recess 10 is located, in which the lower portion of a vertically dis- 50 posed cutting element or knife 11 is arranged. The recess 10 receives a plug 12 which closes said recess at the rear thereof, and this plug is re- 55 tained in place by means of screws 13 which are screwed into the rear wall of the base in such manner that the head portions thereof overlap the plug. The plug 12 is cut away, as

indicated at 14 in Fig. 3, to provide a guideway for the cutting element 11, and said plug is pro- 60 vided with an additional cutaway portion 15 which provides space for the operation of an element which will be subsequently described herein, by which the cutting element is actuated. The recess 14 formed in the plug 12 provides 65 walls which contact with the cutting element at its rear face and side edges, and the forward face of said cutting element contacts with the 70 face 16 of the rear wall of the base 1. Because of this arrangement a guideway is provided which will effectively guide the cutting element during vertical reciprocatory movement thereof. The rear wall of the base 1 is provided with rear- 75 wardly extended portions 17 at opposite edges of the depressed central portion 18 in which the plug 12 is arranged, and the rear face of the central portion 18 is inclined, as shown clearly in Fig. 3.

Secured to the portion 17 of the base 1 at the right-hand end of the machine when viewed from the front is a plate 19, which is provided with a horizontal flange 20 through which fastening devices 21 pass which secure said plate to the 80 base 1. The plate 19 at its upper end is pro- 85 vided with a laterally extended flange 22, and adjacent to the inner edge of said plate an up- standing bearing 23 is provided. Rigidly sup- 90 ported by the bearing 23 is a pin 24', which ex- 95 tends in a direction parallel with the plate 19 and beyond same, and pivotally supported by said pin is a guiding member 24. The guiding mem- 100 ber 24 comprises a vertically disposed element having a guideway formed therethrough, and said guiding member has ears 25 formed thereon which embrace the pin 24' in a manner to pro- 105 vide for pivotal movement of said guiding mem- 110 ber with respect to said pin. The upper end portion of the cutting element 11 is arranged in the guideway of the guiding member 24, and said cutting element reciprocates in said guideway when reciprocatory motion is applied thereto.

26 designates a gauge plate which serves to reg- 100 ulate the thickness of the slices produced by the slicing machine. This plate is arranged in hori- 105 zontal alinement with the plate 19 already re- ferred to herein at the opposite side of the cutting element 11, and as will presently appear, is arranged for adjustment so that its inner edge may be moved transversely with respect to the cutting edge 11' of the cutting element. The gauge plate 26 is provided with a plurality of rear- 110 wardly extended ears 27, there being two pairs of these ears, and the ears of each pair being

arranged in vertical alinement with each other. 28 designates a pair of arms which serve to adjustably support the gauge plate 26, each of said arms having an end portion thereof interposed 5 between a pair of vertically alined ears 27, and a pin 29 being extended through said ears and the end portions of the ram located therebetween, whereby the arm is pivotally attached to the gauge plate. Supported for axial rotation in 10 openings formed in the base 1 is a pair of vertically arranged rods 30, and said rods 30 at their upper ends are rigidly fixed to the ends of the arms opposite to the ends thereof, which are pivotally connected to the gauge plate. The 15 lower faces of the arms 28 rest on the top face of the base 1, whereby the elevation of the plate 26 is maintained, and also the rods 30 are rotatable to swing the outer ends of the arms 28 in an arc of a circle and in this manner adjust the gauge 20 plate forwardly and rearwardly with respect to the cutting edge 11' of the cutting element 11.

Rigidly fixed to the lower ends of the rods 30 is a pair of operating arms 31 which are pivotally connected together at their outer ends by a link 25 32. The link 32 is preferably curved, as shown in Fig. 1, so as to avoid having a portion thereof located beneath the aperture 33, and 34 designates a bell-crank lever which has a leg thereof pivotally attached to an end portion of the link 32, 30 The bell-crank lever 34 is pivoted at 35 to the base 1 and includes an elongated operating arm 36 which extends outwardly beyond the base of the machine. The base 1 is provided with a plurality of spaced extensions 37 arranged in arcuate 35 formation, and the bell-crank lever 34 is provided with an element 38 which is movable into the spaces between the various adjacent extensions 37 so as to lock said bell-crank lever against accidental movement after same has been set. Also, 40 the base 1 has fixed to it a plate 39 provided with graduations with respect to which the operating arm 36 of the bell-crank lever 34 is moved, said graduations indicating the degree of movement of the operating arm 36 to obtain slices of pre- 45 determined thicknesses.

Supported beneath the top wall of the base 1 of the machine is a suitable electric motor M arranged with its armature shaft M' disposed vertically, as shown clearly in Fig. 3. The armature shaft M' of the motor M has fixed thereto by means of a key 40, for instance, an element 41 (Fig. 4), said element being provided at its upper portion with an externally screw-threaded portion 42, and having an inclined annular face 43. 50 44 designates an internally screw-threaded ring which is screwed on the screw-threaded portion 42 of the element 41, said ring being provided with an inclined face 45 which is arranged in opposed relation with respect to the inclined face 43. 46 designates an annular member which surrounds the element 41, said annular member 46 being provided with an annular inclined face 47, and being provided with an internally screw-threaded portion 48. Screwed into the internally 55 60 65 70 75 threaded portion 48 of the member 46 is a ring 49 which is provided with an annular inclined face 50. The annular inclined faces 43, 45, 47, and 50 provide a ball raceway in which anti-friction balls 51 are arranged.

52 designates an arm which is provided with a yoke portion 53 that partially embraces the annular member 46. The extreme outer end of the arm 52 is extended through an aperture 54 (Fig. 4) formed in the lower end portion of the cutting element 11, and the ends of legs of the yoke por-

tion of said arm are pivoted to a pair of upstanding lugs formed on the casing of the electric motor M. The annular member 46 is provided with a forwardly extending element 55 which is circular in cross-section and extends into a correspondingly shaped opening 56 in the arm 52.

A very important feature of the mechanism just described is that the element 41 is fixed on the armature shaft M' of the motor in a plane at an acute angle relative to the axis of said armature shaft, hence, when the armature shaft is rotated, the element 41, and with it the ring 44, will "wobble." This "wobbling" motion is transmitted through the anti-friction balls 51 to the annular member 46 and ring 49, and because the member 46 is connected to the arm 52 through the instrumentality of the element 55, the outer end portion of said arm 52 will be caused to rise and fall in an arc of a circle, whereby vertical reciprocatory movement will be imparted to the cutting element 11. Due to the "wobbling" character of the motion of the annular member 46 there will be slight oscillating movement between the element 55 and the wall of the opening 56 in which said element is extended, and the circular cross-sectional shape of said element and opening will permit such movement.

The base 1 of the machine is provided with a recess 57 (Fig. 3) in which a guiding member 58 is arranged. This guiding member is preferably 105 in the form of a tubular element which is extended longitudinally of the base 1 and is supported at its opposite end by suitable means, such as the members 59 which are fixed to the base 1. Also the base 1 is provided with a track 60 110 which likewise extends longitudinally of said base.

Supported by the guiding member 58 and the track 60 for movement longitudinally of the machine is a carriage 61. The carriage 61 includes a tubular element 62 which embraces the guiding member 58, and also said carriage is provided with suitable shoes 63 which rest upon the top face of the track 60. When viewed in front elevation the carriage 61 is substantially U-shaped (Fig. 2) and the upstanding wall 61' 120 at the right-hand side of the carriage is provided with spaced apart lugs 64 which support a rod 65 (Fig. 1). The rod 65 extends from front to rear of the carriage, and slidably supported thereby is a supporting element 66, said supporting element being provided with eye portions 67 through which the rod extends and including a downwardly extended portion 68 and a horizontally extended portion 69, the latter of which is extended parallel with and in slightly spaced relation with respect to the top face of the bottom wall of the carriage. As already stated, the supporting element 66 is slidable with respect to the carriage 61, and tracks 70 are provided at the top face of the bottom wall of the carriage 135 to facilitate such movement.

Mounted for sliding movement on the rod 65 is a follower which comprises an arm 71 provided with eye portions 72, through which the rod 65 is extended, and a substantially L-shaped plate 73 fixed to said arm. The L-shaped plate 73 is comprised of a horizontally disposed portion which is arranged parallel with and in slightly spaced relation with respect to the portion 69 of the supporting element 66 and a substantially vertical plate portion formed integral with the horizontal portion. The follower is provided with a handle 74 for moving same forwardly and rearwardly with respect to the carriage, and because the eye portions of the arm 140 145 150

- 71 of the follower are interposed between and in contact with the eye portions 67 of the supporting element, said supporting element will be moved with said follower. The portion 69 of the 5 supporting element 66 is provided with upstanding prongs 75, and the horizontal and vertical portions of the L-shaped plate of the follower are provided with prongs 76 which extend downwardly and forwardly, respectively.
- 10 The base 1 is provided with a depression 77 (Fig. 3), which is located between the portion of the base which supports the track 60 and the rear, upstanding flange portion 78 of said base. Because of its location, the task of keeping this 15 depression clean may be rather difficult. The present invention, therefore, includes the use of a strip of substantially U-shaped metal 79, which is snapped in place in this depression by having its edges engaged beneath the track 60 and an element 80. Also, this strip is provided with a pair of openings 81 which are arranged in registration with similar openings 33 and 82 formed in the top wall of the base 1. The carriage 61 is provided with a brush comprising a downwardly 25 extending piece of fiber 83, or other suitable material, which is shaped to fit closely within the cavity provided by the U-shaped strip, and as the carriage is moved back and forth with respect to the base 1, the brush 83 will move any scraps or cuttings which fall into the cavity provided by the U-shaped strip to the openings 81—82 at opposite ends of the base 1, through which 30 said openings said scraps or cuttings will fall. When it is desired to clean and polish the U-shaped strip, same may be readily removed from its place in the structure by springing the edges out of engagement with either the track 60 or the element 80, whereupon said strip may be lifted 35 out of the cavity 77.
- 40 In the operation of the improved slicing machine, the material to be sliced is supported by the carriage 61 and said material is moved rearwardly of said carriage by the follower. If desired the material being sliced may be clamped 45 between the horizontal plate portion of the follower and the portion 69 of the supporting element 66 during such rearward movement of said material, or, if preferred, the material may be moved rearwardly of the carriage by arranging 50 the rear end thereof in contact with the vertical plate portion of the follower and moving said follower rearwardly. The operator grasps 55 the handle 74 and moves the carriage back and forth with respect to the machine, at the same time keeping the material pressed rearwardly by forcing the follower in that direction, and each time the material is moved from left to right of the machine and with respect to the rapidly reciprocating cutting element, a slice is cut therefrom, which slice falls on the pan P.

When it is desired to remove the cutting element 11 from the machine the fastening devices 13 may be removed and the plug 12 displaced from its position. The lower end portion of the cutting element may then be moved rearwardly, the guiding member 24 swinging on the pivot 24' in response to such rearward movement of the lower portion of the cutting element, and when the cutting element has been moved to the approximate position in which it is shown by dotted lines in Fig. 3, it may be moved downwardly so as to withdraw the upper portion thereof from the guiding member 24.

I claim:

1. A slicing machine comprising a cutting element, means for supporting said cutting element for straight line movement, said means including a pivotally mounted guiding member located at an end of said cutting element, means for subjecting said cutting element to reciprocatory movement, and a carriage movable transversely of the path of movement of said cutting element for supporting material being sliced, said pivotally mounted guiding member being fixed with respect to said cutting element when said cutting element is subjected to reciprocatory movement.
2. A slicing machine comprising a cutting element, means for supporting said cutting element for straight line movement, said means including a pivotally mounted guiding member located at an end of said cutting element, and a second guiding member located at the opposite end of the cutting element and detachable from the machine, means for subjecting said cutting element to reciprocatory movement, and a carriage movable transversely of the path of movement of said cutting element for supporting material being sliced, said pivotally mounted guiding member being fixed with respect to said cutting element when said cutting element is subjected to reciprocatory movement.
3. A slicing machine comprising a cutting element, means for supporting said cutting element for straight line movement, said means including a pivotally mounted guiding member located at an end of said cutting element, and a channeled guiding member located at the opposite end of the cutting element and detachable from the machine, means for subjecting said cutting element to reciprocatory movement, and a carriage movable transversely of the path of movement of said cutting element for supporting material being sliced, said pivotally mounted guiding member being fixed with respect to said cutting element when said cutting element is subjected to reciprocatory movement.

ADOLPH RUBIN.
